Samuel F. Stowe, of Providence R. I.

Assignor to

Hinsley & Levi & Co. Stone of the same place
Letters Patent No. 2325. Dated May 22, 1866.

Design for a Trade mark.

The schedule referred to in these Letters Patent and nothing part of the same

To all whom it may concern:

Be it known that I Samuel F. Stowe of the City and County of Providence in the State of Rhode Island have invented originated and designed a new design for a trade mark reference being had to the accompanying specification and drawings making a part of the same,

My design for a trade mark is to be used to designate a coding beverage the recipe for which is known to me.

The design consists in the use of a goblet A represented as overflowing with the foaming beverage and surrounded with a vine wreath B. Between the goblet and the wreath at the top I insert the words "Magic fluid" and above the wreath in a curved line the words "the great temperance drink" and underneath the wreath the descriptive words "Ambrosial nectar" I do not claim the phrase or words used as descriptive of the qualities of the article. But what I do claim as my invention and desire to secure by Letters Patent is the design for a trade mark consisting of a foaming goblet and surrounding floral wreath as shown and described
